CARBURETOR

Gunnar Clavering, Toronto, Ontario, Canada, assignor of fifteen per cent to Kathleen Clavering, twenty per cent to James W. Ralston, five per cent to Alfred E. Matthews, five per cent to Albert E. Reader, and forty per cent to Mildred C. Johnston, all of Toronto, Ontario, Canada

Application September 28, 1942, Serial No. 460,024

8 Claims. (Cl. 261—34)

This invention relates to improvements in carburetors particularly for use with the ordinary type of internal combustion engines used in motor vehicles and the principal object of the invention is to devise a structure which will enable the use of a heavier fuel than is ordinarily employed and is particularly adapted for use with fuel oil.

The principal feature of the invention consists in providing means for conducting the fuel oil from a well or reservoir by capillary attraction and the influence of the engine suction which will present extensive oil saturated surfaces to the flow of air thereover to effect the carburetion of such air and produce an explosive mixture capable of operating an internal combustion engine.

A further important feature consists in the arrangement of an oil duct leading to the carburetion chamber having a wick arranged therein to break up the oil stream, a force pump being connected with said oil duct to effect a forced flow of oil through said wick to provide an instantaneous distribution of oil in the carburetion chamber to effect immediate carburetion for starting the engine.

A still further feature of the invention consists in the novel construction of the air passage through the carburetion chamber whereby turbulence in the air flow is effected in the locality of the oil saturated surfaces whereby the maximum of carburetion of the air may be effected.

Another feature of importance consists in the conduction of heated air around the oil conduction and airflow passages to reduce the viscosity of the oil and increase its volatility.

In the accompanying drawings Figure 1 is a part plan and part sectional view of my improved carburetor, the section being taken on the line 1—1 of Figure 3.

Figure 2 is a longitudinal vertical section through the carburetor taken on the line 2—2 of Figure 1.

Figure 3 is a vertical cross section through the carburetor taken on the line 3—3 of Figure 1.

Figure 4 is an enlarged vertical longitudinal mid-section of the means for conducting the oil to the carburetion chamber.

Figure 5 is an enlarged detail sectional view through the air inlet valve to the carburetor.

Referring to the accompanying drawings, the main body of the carburetor is formed of a bottom section 1 and a cap section 2 through which a longitudinal cylindrical passage 3 extends to a widened chamber 4 at one end which also communicates with longitudinal channels 5 arranged

on either side of and parallel with the central cylindrical passage 3.

The end of the central passage 3 opposite to that connected with the chamber 4 is connected with a converging passage 6 arranged in the extension 7 of the casing in which the throttle control valve 8 is mounted.

The longitudinal side channels 5 are connected at the ends opposite to the chamber 4 with a passage 9 extending beneath the passage 6 and the passage 9 opens through the flanged side wall 10 in which an air inlet valve is arranged. The flanged opening from the passage 9 is connected with a suitable source of heated air by a pipe 11.

15 The preferred form of air inlet valve is shown in enlarged detail in Figure 5 and consists of a flange 12 formed with a valve seat 13 secured to the flange 10 and having a spider extension 14 in which is slidably mounted a spindle 15 which is rigid with a spider extension 16 of a ring valve 17 which engages the seat 13. The ring valve 17 is provided with a valve seat 18 which is engaged by a valve 19, the spindle 20 of which is slidably mounted in a spider extension 21 carried by the 25 ring valve.

Coil compression springs 15' and 20' surround the valve spindles 15 and 20 respectively. The spring 20' is lighter than the spring 15' and opens under a light pressure to admit a restricted flow 30 of air and as the engine throttle is opened and a greater flow is required the large valve opens to increase the inlet area.

A chamber 22 which is shown of D shape in cross section is formed at one side of the main 35 casing of the carburetor and forms the float chamber for controlling the supply of fuel. An air passage 23 is formed in the wall of the chamber 22 and communicates at one end with one of the side channels 5 at the inlet end, the other end thereof 40 opening into the chamber 4. A passage for heated air is thus provided surrounding the float chamber.

A suitable type of float valve 24 is mounted in a boss 25 in the side wall of the float chamber 45 and an adjusting yoke 26 carried by the threaded spindle 27 mounted in the cap of the float chamber supports the float 28.

Within the central portion of the bottom section 1 of the carburetor between the side channels 5 are formed a pair of vertical cylindrical orifices 29 and within each of said orifices is arranged a cylindrical member 30 provided with a flange 31 at the top which supports the said member above the bottom of the orifice, thus 55 forming a well space 32 at the bottom.

Each of the members 30 is provided with a central orifice of circular cross section formed with inwardly converging walls 33 forming a convergent throat which is flared outwardly at the top.

Cords 34 of textile wicking are laid longitudinally of the circular orifice of the member 30 and these are fitted snugly together in the throat portion with the upper ends turned outwardly over the tops of said members and secured by binding rings 35. The bottom ends of the cords 34 extend outwardly and are secured by the binding rings 36. These cords are immersed in the fuel oil to the level determined by the float valve and the oil is conducted upwardly by capillary attraction to the outwardly flaring upper ends which are located on the bottom of the carburetion chamber 3.

A flanged block 37 closes the bottom ends of the orifices 29 and channels 38 arranged horizontally of the block lead to the chambers 32 from the float chamber 22.

Spindles 39 slidably and non-rotatably mounted in packing glands 40 in the block 37 extend upwardly into the members 30 and are provided with heads 41 bevelled to correspond with the bevel of the convergent throats. These bevelled heads are adapted to be adjusted vertically to engage the oil-conducting cords to regulate the upward flow of oil. The lower ends of the spindles 39 are rotatably mounted in nuts 42 threaded in the block 37.

The cap section 2 is formed with a pair of dome-like cavities 2' arranged vertically over the vertical orifices 29 and form means for creating turbulence in the air stream flowing through the chamber 3 at points opposite the said orifices.

Between the vertical orifices 29 is formed a vertical duct 43 leading to an enlarged threaded recess 44 opening upwardly between said orifices into the chamber 3 and within said threaded orifice is a threaded ferrule 45 flanged at the top to engage the flanges 31 of the members 30 to hold them securely in position.

Within the central orifice 46 of the ferrule 45 is a wick 47 of cords which flare outwardly at the top and are secured at the bottom by a fastening ring 48.

A duct 49 extends laterally from the bottom end of the duct 43 and is connected by a pipe 50 to the discharge opening 51 of a small force pump 52 mounted on the bottom section 1 of the carburetor in a suitable position. A ball valve 53 is provided in the discharge orifice to permit the flow of oil from the pump cylinder but acts as a check to prevent back flow on the up-stroke of the pump piston 54.

Oil is conducted to the pump by a pipe 55 which is provided with a check valve 56 to allow inflow when the piston is raised.

The rod of the piston 54 is connected to a lever 57 suitably mounted on the pump cylinder and said lever is connected in a suitable manner with the accelerator pedal of the vehicle on which the carburetor is installed so that on the initial impulse of the accelerator the pump piston is depressed and a charge of oil is forcibly projected from the pump through the ducts 49 and 43 and through the wick mounted in the ferrule. The stream of oil forced through the wick is broken up as it enters the chamber 3 and is readily absorbed by the air flowing through said chamber.

A Venturi tube 58 with a convergent throat is inserted in the passage 6 to regulate the air flow

to the engine in accordance with its cylinder capacity.

This Venturi tube is preferably provided with extensions 59 which may pass either side of the members 30 and the depth of such extension which pass under the flanges 31 may be varied to raise or lower the members 30 in accordance with the requirements of the engine with which the carburetor is to be used.

The extremities of the Venturi bars support a drip flange 60 to prevent any surplus of oil from the wicks 34 dripping into the air channels leading to the carburetion chamber 3.

In the use of this carburetor an oil supply tube is connected with the entrance to the float valve 24 and oil is admitted to the chamber 22 and maintained at the desired level. The oil flows from the chamber 22 through the channels 38 to the well spaces 32 at the bottom of the orifices 29 and immerses the lower ends of the wick cords. The oil saturating these cords travels upwardly to the outwardly flared upper ends which present an extensive oil-saturated area along the bottom of the central air passage 3.

Heated air from an exhaust or other heater is directed into the passage 9 and flows through the side passages 5 and around the float chamber through passage 23 to the chamber 4 which directs it up to the inner end of the central carburetion passage 3. The heated air flowing through these passages heats the oil and then entering the passage 3 it strikes the dome cavities 2' arranged over the tops of the wick members 33. The heated air thus swirling over the oil-saturated areas picks up oil vapours to form an explosive mixture.

The engine suction exerts a lifting influence in the central orifices of the wick-bearing members 30 and the oil flow is regulated in accordance with engine requirements by adjusting the members 41 to engage the wicks with the proper repressive pressure.

In starting the engine, the surface oil at the top of the wicks may have receded and it is desirable that oil be projected into the air passage 3 to mix with the air drawn through such passage by the suction of the engine. This is effected by the operation of the force pump described, the plunger of which is connected with the throttle or accelerator pedal. The forceful projection of a small quantity of oil through the duct 43 and wick 47 sprays oil into the air flowing through the passage 3 and this is accelerated by the flow through the Venturi tube.

A carburetor such as described will produce an explosive mixture from fuel oil which has been found to operate the ordinary automobile engine effectively and economically and it can be manufactured at very moderate cost. Further, there are no delicate or intricate parts to get out of order.

What I claim as my invention is:

1. A carburetor having a horizontal tubular carburetion chamber through which a stream of air is drawn, an oil supply well arranged below said chamber, a plurality of openings arranged longitudinally in the bottom of said tubular carburetion chamber and extending downwardly into said oil supply well, wicks arranged in said openings and conducting oil by capillary attraction from said oil well to the bottom of said carburetion chamber, a force pump connected with an oil supply, and an oil duct leading from the discharge of said oil pump and directly entering the bottom of said carburetion chamber between a

pair of said wick openings to project a jet of oil into the carburetion chamber.

2. A carburetor having a horizontal tubular carburetion chamber, an oil supply well arranged below said chamber having an opening in the top extending through the floor of said chamber intermediate of its length, an air passage extending around said oil well and communicating with the inlet end of said carburetion chamber to conduct a flow of heated air around the oil well and deliver same to the carburetion chamber, a wick in said oil well extending to the top opening thereof to conduct oil to the floor of said carburetion chamber, and adjustable means for regulating the flow of oil through said wick.

3. A carburetor as claimed in claim 2 having a tubular member arranged in said oil well and extending through the top opening thereof and formed with a converging throat and supporting said wick, said wick having its upper end spread laterally outward, and annular means encircling and securing the outspread upper end of said wick on the floor of the carburetion chamber.

4. A carburetor as claimed in claim 2 having a tubular member arranged in said oil well and extending through the top opening thereof and formed with a converging throat and supporting said wick, a vertically adjustable spindle extending through the bottom of said oil well formed with a bevelled head to engage and constrict the wick against said convergent throat, and means engaging the lower end of said spindle for adjusting same vertically.

5. A carburetor having a horizontal tubular carburetion chamber, an oil supply well arranged below said chamber having an opening in the top

extending through the floor of said chamber intermediate of its length, an air passage extending around said oil well and communicating with the inlet end of said carburetion chamber to conduct a flow of heated air around the oil well and deliver same to the combustion chamber, a float chamber at one side of said oil well having an air duct extending therearound and communicating with the air passage extending around the oil well, and means for feeding oil to the floor of the carburetion chamber.

6. A carburetor having a horizontal tubular carburetion chamber through which a stream of air is drawn, an oil supply well arranged below said chamber, means for conducting fuel oil upwardly from said well by capillary attraction entering said carburetion chamber intermediate of its length and presenting oil saturated surfaces on the bottom of said chamber and having an oil duct leading directly to the carburetion chamber, a force pump connected with said oil duct to force a jet of oil to said carburetion chamber, and a wick arranged at the outlet of said oil duct adapted to break up the oil jet entering said carburetion chamber.

7. A carburetor as claimed in claim 6 having a ferrule surrounding said wick secured in the discharge end of said duct, and means for rigidly securing the inner end of said wick to said ferrule.

8. A carburetor as claimed in claim 6 in which said force pump has its discharge connected with said oil duct and its intake connected with an oil supply and is provided with a piston, and manually operable means is connected with said pump piston for operating same.

GUNNAR CLAVERING.
